MODEL SURFACE FINISH

Philip L. Mates, Park Ridge, and John J. Andrews, Streamwood, Ill., assignors to Hawk Model Company, Chicago, Ill., a corporation of Illinois

Filed Oct. 8, 1962, Ser. No. 229,125

2 Claims. (Cl. 117—8)

The present invention relates generally to plastic models and specifically to a surface finish for plastic models coated by vacuum metallizing which accurately conveys the visual impression in a model of a sheet metal sheathed prototype.

A high degree of perfection has been achieved in the model industry in faithfully reproducing the shape of prototypes in small scale plastic models. In cases where the prototypes for the models constitute sheet metal covered machines, such as airplanes, trucks, tanks, steam shovels, etc., attempts to reproduce the metallic qualities of the surface have not been completely successful.

It is well known to coat such plastic models, as for example a model of an airplane, with a layer of aluminum applied by a standard vacuum metallizing technique. In this technique the plastic part is mounted within a vacuum chamber and a relatively high current is passed through an aluminum filament. The aluminum vaporizes and the individual aluminum particles are then deposited upon the plastic part and adhere thereto forming an extremely thin aluminum coating. This coating may then be covered with a layer of lacquer for protective purposes. Although such treatment substantially enhances the visual appearance of the plastic part as compared with a similar painted item, the surface has a uniform shiny appearance wherein adjacent areas are identical in surface texture. Of course, the prototype of such a model, for example an airplane, does not have a uniform surface appearance. Since the surface of the airplane is constructed of a plurality of individual sheet metal parts, many of which are of differing alloy mixtures and which have been subjected to differing manufacturing techniques, the surface textures of adjacent sheet metal parts are often different. Therefore, any model which seeks to accurately convey the rough appearance of the prototype must similarly have individual discreet surface areas of differing surface textures.

Accordingly, it is an object of the present invention to provide a surface for plastic models of metallic prototypes wherein the surface qualities of the prototype are accurately conveyed in the models. Specifically, it is an object of the present invention to provide models having differing surface textures on differing discreet surface areas of the models and to provide a method for the manufacture thereof.

In accordance with the present invention, there is provided within a plastic model a surface treatment including border indicia defining discreet surface areas representing the respective areas on the skin of the prototype. The several discreet areas of the model are provided with differing surface textures including high polishes on some of the areas, visible honing in one direction on other areas, further visible honing in another direction on still other areas, and non-directional water honing on still further areas to produce a plurality of surface textures across the surface of the model.

In accordance with method aspects of the present invention, there is provided a method for the manufacture of plastic models which includes as a first step the formation of border indicia within the die or mold for the model to define discreet surface areas. The surface areas are then textured in differing patterns by the use of high polishes on some of those areas, stone honings in various directions on other of those areas and liquid honings on

2

still further areas to produce a satin finish. The plastic model is then molded within the mold or die to produce a plastic model incorporating such textured surface areas. The plastic part is placed within standard vacuum metallizing chambers in order to apply an aluminum coating thereon such to produce a metallic multi textured surface in simulation of the metallic multi textured surface of the prototype.

The above brief description, as well as further objects, features and advantages of the present invention, will be best appreciated by a reference to the following detailed description of one presently preferred embodiment of the invention when taken in conjunction with the accompanying drawings wherein:

15 FIGURE 1 is a diagrammatical process flow chart representing the various steps in the practice of the present invention;

15 FIGURE 2 is a side elevational view of the fuselage of an airplane model incorporating a surface treatment of the 20 present invention;

20 FIGURE 3 is a plan view of the top of a wing section for a model airplane constructed according to the teachings of the present invention; and

25 FIGURE 4 is a chart designating the various surface treatments as indicated in FIGURES 2 and 3.

Referring specifically to the drawings, there is shown in FIGURES 2 and 3 a fuselage section 10 and a wing section 12, respectively, each of which is constructed according to the teachings of the present invention. Specifically, it may be seen that the surface of the model sections 10, 12, have been formed with a plurality of border indicia which, in the present illustrative case, comprise ridges and/or depressions as indicated at 14 and rivets as indicated at 16. These border indicia 14, 16 effectively define a plurality of discreet surface areas. For clarity of description those areas immediately adjacent the end of the wing are labeled A, B, C, D and E. It will be appreciated, of course, that the border indicia 14, 16 are formed such that the surface areas A, B, C, D, E, etc., conform to the areas of individual pieces of sheet metal as applied to the prototype of the given model. For example, the skin of an aircraft is commonly constructed of a number of sheets of aluminum or aluminum alloy which are riveted or welded to a frame in order to form a completed skin for the aircraft. The visual appearance conveyed by these separate pieces of metallic sheeting are reproduced in the model by providing border indicia 14, 16 and points corresponding to the edges of the several sheets of metal thus forming the discreet model areas A, B, C, D, E, etc. corresponding to the several sheets of metal on the prototype.

According to the present invention, the various surfaces of the discreet model areas A, B, C, D, E, etc., are treated with a variety of textures to more accurately simulate the appearance of the prototype. Specifically, the enumerated 55 discrete areas A, B, C, D, and E, as may be seen by correlating the surface indications in FIGURE 3 with the surface texture key on the drawings, have respectively, a horizontally directed matte finish, a highly polished shiny surface, a vertically directed matte finish, a non-directional 60 matte finish, and a further non-directional matte or satin finish. Further examination of the drawings will reveal further random placement of individual discreet surface areas having a variety of surface textures.

In accordance with the method aspects of the present 65 invention, model parts, such as the fuselage 10 and wing 12, as illustrated in FIGURES 2 and 3, are manufactured according to the process outlined in the flow diagram of FIGURE 1. The negative shape of the desired plastic model section is formed in a mold according to well known 70 technology and includes the negative shape of the various surface indicia which will effectively define the discreet

surface areas on the plastic model parts. After the general configuration of the mold is established, the negative surfaces of the mold are textured in order to produce corresponding textures on the finished plastic parts. Specifically, within the discreet surface areas as defined by the border indicia, the mold is provided with a number of different surface treatments. For example, one surface may be polished to a high degree of lustre by conventional polishing equipment and adjacent areas may be microscopically scratched with an oil stone in a given direction to provide a rough treatment having directional surface qualities. Still further adjacent areas may be abraded with an air stream containing abrasive particles to produce a matte surface of varying roughness in either a directional or non-directional manner. Furthermore, the directional characteristic from one roughened surface to another may be varied to produce differing appearances in the finished model.

Following the preparation of the mold, the parts are molded and directly after molding are subjected to a vacuum metallizing technique prior to any application of a surface covering which might smooth over the texture applied to the plastic model sections by the textured surfaces of the mold. The vacuum metallizing process which is utilized to provide a metal finish to the plastic part is accomplished according to processes well known in the art.

It will be appreciated that the present invention provides a metal coated plastic model construction which effectively and faithfully reproduces the visual characteristics of a metal prototype and further provides a process for the manufacture thereof. Due to the fact that prototype objects which are sheathed with sheets of metal have surfaces which vary from one particular piece of metal to the next adjacent piece, it has heretofore been difficult to effectively reproduce the visual impression of those prototypes in plastic models, even when the models have been provided with a metallic surface finish. However, the applicant, by the invention disclosed herein has obviated these prior failings in the model making art.

The foregoing is a description of just one illustrative embodiment of the present invention. Other embodiments may be produced incorporating the invention by the application of ordinary design skill. Therefore, the following claims should be interpreted broadly in a manner consistent with the spirit and scope of the invention.

What we claim is:

1. In a plastic model of a sheet metal sheathed prototype, a surface in simulation of the surface of the proto-

type comprising a plurality of border indicia formed integrally in the surface of said plastic model defining a plurality of discreet surface areas, said surface areas having different surface textures formed in the plastic of said model, some of said surface areas having a smooth polished plastic surface, other of said surface areas having a plurality of fine lines formed in the plastic surface in a first direction, still other of said surface areas having a plurality of fine lines formed in the plastic surface in a second and different direction, and still other of said surface areas having a matte finish formed in the plastic surface, and a vacuum metallized layer superimposed over the entire surface of said plastic model and on said surface areas and said border indicia and conforming to the different textures thereof for forming an accurate appearance of the sheet metal sheathed prototype.

2. In a plastic model of a sheet metal sheathed prototype, a surface in simulation of the surface of the prototype comprising a plurality of border indicia formed integrally in the surface of said plastic model defining a plurality of discreet surface areas, said surface areas having different surface textures formed in the plastic of said model, and a vacuum metallized layer superimposed on the entire surface of said plastic model and on said surface areas and said border indicia and conforming to the different textures of said surface areas forming an accurate appearance of the sheet metal sheathed prototype.
